W. L. HARROUN

FLUSH VALVE

Filed Sept. 4, 1924

UNITED STATES PATENT OFFICE.

WILLIAM L. HARROUN, OF ELLISBURG, NEW YORK.

FLUSH VALVE.

Application filed September 4, 1924. Serial No. 735,964.

To all whom it may concern:

Be it known that I, WILLIAM L. HARROUN, a citizen of the United States, residing at Ellisburg, in the county of Jefferson 5 and State of New York, have invented certain new and useful Improvements in Flush Valves, of which the following is a specification.

This invention relates to improvements in 10 flush valves, designed for use in connection with water-closet flush tanks, and has for its object the provision of novel and positive means for seating the flush valves following each flushing operation. A further 15 object is to provide a novel disc valve, which is supported by and is movable with the usual spherical rubber valve, the said auxiliary valve, during the flushing intervals, being disposed in the path of, and being 20 drawn downwardly into the flush pipe by, the strong suction of the flushing stream, thereby positively and truly seating the flush valve. And a particular object is to 25 improve and simplify the means by which the auxiliary valve is secured to, and by which the flush valve is supported and operated.

The present invention has for its definite 30 object the reduction of the number of parts, as well as the cost, of the valve operating devices shown and described in my United States Patent No. 1,374,655, dated April 12, 1921.

The various features and parts of the 35 invention will be understood from the detailed description which follows, and by reference to the accompanying drawing, in which—

Figure 1 is a vertical longitudinal section through a flush tank, to which my invention 40 is applied. Fig. 2 is an enlarged view, partially in section, of the flush valve and flush pipe; showing the closed and open position of the valve. Figs. 3 and 4 are similar enlarged views of the disc valve and the one- 45 part operating rod. Fig. 5 is a bottom face view of the disc valve. Fig. 6 is respectively an end and an edge view of the threaded bushing which is embedded in the top of the flush valve. Fig. 7 is a view showing the operating rod in two parts. And Fig. 8 is an enlarged view of the threaded portion of the rod and the bushing.

In the drawing, 2 represents a flush tank, 50 which receives the flushing water through a pipe 3, the incoming water being controlled by a ball-cock 4 and a float 5. 6 represents

the usual flush pipe, by which the water is discharged from the tank, the upper end of said pipe, which projects into the tank, comprising the usual flaring seat for the flush 60 valve 7, the latter being seated by gravity, and unseated for discharging the tank, by means of connected rods 12 and 13. The flush valve 7 preferably consists of a hollow spherical rubber part, which when lifted for 65 effecting the flushing, as shown by the dotted lines in Fig. 2, owing to its natural buoyancy is held away from its seat 6', until the close of the flushing period, when the suction of the outflowing water draws the valve towards its seat. In the past, more or less trouble has been experienced with the proper seating of flush valves of the class, due to the tendency of said valves, when approaching 70 their seats, to gyrate with the eddying and swirling flushing streams. This frequently causes the flush valve to impinge against one side or the other of the seat, and to become canted to such extent that the flushing is either prolonged, or else the discharge continues like a leak until the valve is restored to its proper position. To overcome this trouble, I provide a valve comprising a disc, as 14, which is normally positioned in the flush pipe 6, preferably in line 85 axially with said pipe and the valve 7. The diameter of the disc 14 is smaller than the bore of the pipe 6, and when the valve 7 is lifted, as shown by dotted lines in Fig. 2, the disc is positioned slightly above the seat 6', 90 directly in the path of the gravitating water. As the water in the tank recedes, the ball 7 and the disc 14 gradually descend, and the last of the flushing stream draws the disc downwardly until it effects the positive seating of the ball. The subsequent 95 refilling of the tank tends to hold the valves 7-14 in the closed position, shown by full lines in Figs. 1 and 2.

In the present case, the valve 7 is provided 100 with top and bottom axial openings 7'-7", for the insertion of the one-part operating rod 13. For this purpose the top opening 7' is provided with an internally threaded metal bushing 15, which is preferably permanently embedded in the material of the valve when the latter is molded. The rod 13 is preferably inserted downwardly through the valve 7, and in order to suitably secure the rod and valve together, the medial 105 portion of the rod is flattened, as at 13', by means of suitable swaging dies, and the

laterally bulging portions resulting from the displacement of the metal are threaded for screwing into the bushing 15, as shown in Figs. 2 and 8, in which the bushing is shown threaded downwardly to a point near the bottom of the opening, and below the threaded portion the opening of the bushing is preferably plain and substantially the same diameter as the unflattened portion of the rod, for preventing leakage through the said opening into the valve 7. The lower end of the rod 13 is also threaded and screws into a central threaded opening of the disc 14. The top end of the rod 13 is preferably formed with a loop 13^a, which is shown engaged by the hook-end of the operating rod 12. Between the valve 7 and the rod 12, the rod 13 passes loosely through a guide 16, which is supported by the usual overflow pipe 17 common to tanks of the class.

The rod 13 takes the place of the rods 8 and 10 and the collar 10', of my former patent, and the bushing 15 replaces the former sleeve 11. This change in the construction and arrangement of the operating parts has been rendered necessary, in order to reduce the cost of making and assembling the parts, and particularly for the reason that the continual jars and vibrations resulting from the more or less jerky and rough handling of the flushing mechanism by the users of the closet, tends to loosen the former complicated operating parts, and seriously interferes with the proper and effective operation of the flushing mechanism.

To apply my improved flushing mechanism to a tank of the class shown, the plumber takes the rod 13 and inserts its threaded end downwardly through the guide 16, the lower end of the rod is next passed downwardly through the valve 7, and the

threaded portion 13' is screwed into the threaded socket of the bushing 15 until it comes to a stop, as shown in Figs. 2 and 8. The connected rod and valve are then lifted upwardly, as from the full line to the dotted line position shown in Fig. 2, for applying the disc 14 to the threaded lower end of the rod. This completes the assembling of the several parts of the invention, as well as the installing of the same in the tank.

In Fig. 7 the rod 13^b is shown in two parts, which may be screwed into the bushing 15 from opposite directions. By this construction and arrangement, the valves 7 may be applied to the old style of flushing mechanisms, either with or without the valve 14.

Having thus described my invention, what I claim, is—

1. The combination with a flush valve and a disc disposed below said valve, of a threaded bushing embedded in the top of said valve, and a rod passing axially through said valve and disc, the medial portion of said rod being flattened for providing laterally projecting portions which are threaded for screwing into said bushing, and means for detachably securing the disc to the rod.

2. The combination with a flush valve having a threaded bushing embedded in its top end, a flush pipe, and a disc-shaped valve spaced below the flush valve, of a rod inserted downwardly through the flush valve and supporting said disc valve concentrically in said pipe, said rod having its medial portion flattened and the bulging lateral sides thereof being threaded for screwing into the bushing.

In testimony whereof I affix my signature.

WILLIAM L. HARROUN.
